UNITED STATES PATENT OFFICE.

JOHN F. HILL, OF MAYETTA, KANSAS.

WIRE-STRETCHER.

1,285,174.

Specification of Letters Patent. Patented Nov. 19, 1918.

Application filed February 8, 1918. Serial No. 216,049.

To all whom it may concern:

Be it known that I, JOHN F. HILL, a citizen of the United States, residing at Mayetta, in the county of Jackson and State of 5 Kansas, have invented certain new and useful Improvements in Wire-Stretchers, of which the following is a specification.

This invention relates to wire working, and more especially to wire stretching implements; and the object of the same is to produce a wire stretcher by means of which the workman can take up the initial slack in a long stretch of fence wire and then give the 10 final stretching or tightening to the same and hold it in that position while it is fastened to the post or posts.

This object is carried out by giving the implement the construction herein described and claimed, and reference is made to the 15 drawings, wherein:—

Figure 1 is a plan view of the implement showing it in use, and

Fig. 2 is an edge elevation thereof.

Referring by reference numerals to the 20 drawings, the implement consists of a staff or handle 1 having at its front end a head broadly designated by the numeral 2, which head is bent or hooked or laterally curved as shown to the extent of about one-half of a 25 complete circle. All parts of the head should be of metal, whereas of course the staff may be of metal or of other material. On the outside of the curve and at the forward side of the head is a spur 3 for embedding the 30 earth in a manner yet to be described. On what is shown as the upper side of the head and the outer arm thereof in Fig. 1, are several pins or hooks 4, and perhaps there may be an additional pin or hook 5 in the outer 35 end of the head. The inner end of the head may be carried transversely past the line of juncture of the handle into what might be called a heel 6. The numeral 7 designates broadly a wire clamp disposed about in line 40 with the heel and connected with the staff or handle by a tie 8 which is preferably a stout piece of wire or possibly a bolt as herein shown. The clamp illustrated herein

is seen in Fig. 2 as made of two plates drawn together by a bolt having a wing-nut. 50

With this construction, the application and use of this improved implement is as follows: Taking hold of the staff or handle, which may be four feet long, the operator sinks the spur 3 in the ground, and on drawing on a long stretch of wire and engaging it with the clamp 7, he can then manipulate the handle to take up the initial slack. This use of the device avoids the accident often experienced when a long stretch is to be 60 taken up by hand, the wire or the barbs therein often cutting the hands and injuring the operator. Having taken up the slack the dished side of the laterally curved head is placed around a post as indicated by the 65 letter P in Fig. 1, and the clamp 7 reset on the wire broadly indicated herein by the letter W. The handle is now moved in the proper direction (upward in Fig. 1) to put tension on the wire, whether the stretch of 70 the wire being worked is long or short. As the handle swings around the post, the hooks 75 4 come successively under the wire W, and when the latter has finally been given the desired tension, the handle is manipulated so that the last hook which has passed the wire is engaged with it. The handle may now be released, and the operator is free to 80 staple the wire to the post so as to hold the same applied to it. Then the implement is disconnected and the workman moves along to the next post, and so on. If the outer end of the handle is moved far enough in the direction described, the clamp will be caused to draw up against the heel 6, but said heel 85 is provided with this very end in view. The spur 3 is preferably comparatively thin as best seen in Fig. 2 so that it does not interfere with the swinging of the implement.

The implement may also be used in the 90 nature of a crowbar, or it might be stuck through a roll or reel of netting so that the same could be carried by two men, or rolled along the ground.

What is claimed as new is:—

The herein described wire stretcher com-

prising a handle, a head carried thereby and struck on a semi-circle with its inner arm connected to the handle and projecting laterally to one side thereof to form a heel, a series of hooks upstanding from its outer arm and one hook projecting from its outer extremity, a tie passing through the handle, and a wire clamp carried by said tie and

overlying said heel, the whole constructed substantially as described.

In testimony whereof I affix my signature in presence of two witnesses.

JOHN F. HILL.
